THERMAL TIME DELAY SWITCH

Emil C. Widmer, East Orange, N.J., assignor to Curtiss-Wright Corporation, a corporation of Delaware

Application October 1, 1958, Serial No. 764,673

8 Claims. (Cl. 200—122)

This invention relates to thermal time delay switches of the type using bi-metal elements associated with a heater for opening and closing switch contacts according to predetermined time response, and has for its principal object to provide an improved thermal time delay switch of this character having co-acting contact structure arranged so as to ensure substantially constant pressure between the contacts throughout the period of contact engagement.

A further object is to provide an improved switch of the above type that is reliable and efficient in operation and also simple, inexpensive and rugged in construction.

This invention will be more fully set forth in the following description referring to the accompanying drawing, and the features of novelty will be pointed out with particularity in the claims annexed to and forming a part of this specification.

Referring to the drawing, Fig. 1 is an assembly of the essential parts of a thermal time delay switch embodying the present invention, Fig. 2 is a perspective view of the unassembled spring mounting structure of one of the contacts in Fig. 1, Fig. 3 is a perspective view of the contact structure of Fig. 1 in its normal operative position, and Fig. 4 is a side view of the contact structure shown in Fig. 2.

The switch assembly of Fig. 1 is normally enclosed in an evacuated glass envelope or the like, either with or without special gases for improving contact operations. The envelope is not shown as it forms no part of the present invention. The assembly comprises essentially a supporting base 1 that may comprise an insulating disk 2 that is mounted in a sealing ring 3 for joining the base to the glass envelope. The insulating disk 2 receives the conductor terminals 4 that support the main switch assembly and connect the co-acting contacts and the bi-metal heater to suitable external circuits.

The main switch assembly comprises two bi-metal elements 5 and 6 formed as elongated rectangular strips that are secured at the base ends to an insulating spacer block 7 in clamped relation thereto as indicated by the through bolt 8 and washers 9. Certain of the terminal conductors such as 4b are suitably connected to the bi-metal elements 5 and 6 for completing the circuit between the switch contacts which are mounted respectively on the bi-metals as presently described. The bi-metal 5 is provided with a heater coil 10 that is mounted in insulating arrangement around the bi-metal element according to usual practice. The heater is suitably connected at 10a to the terminal conductors 4a as indicated.

The switch contacts 11 and 12 are carried by the bi-metal elements 5 and 6 respectively. The contact 11 is rigidly mounted at the upper free end of the bi-metal 5 by adjustable means such as a screw fastening 13 constituting the electrical connection with the bi-metal 5. The co-acting contact 12 is resiliently mounted on the bi-metal 6 so that it has limited following movement with the contact 11.

The resilient mounting structure for the contact 12

2

is designed so as to maintain substantially constant pressure between the contacts throughout their travel of contact engagement. To this end, the co-acting contact mounting structure comprises a spring steel strip 13 that is suitably secured to the bi-metal 6 at 14 (as by riveting), said spring strip being formed as an elongated compressed loop that extends approximately half the distance from the securing rivet 14 toward the supporting base including the spacer stack at 7. The spring loop 13 also forms the electrical connection between contact 12 and bi-metal 6. A detent 15 having an overhanging lip 16 is secured to the upper free end of the bi-metal 6 (and may conveniently comprise as indicated an extension of the strip 13) for engaging and restraining the free end 13a of the strip. The loop in this position tends to expand because of the stressed condition of the strip 13.

Figures 2, 3 and 4 more clearly illustrate the spring strip arrangement for ensuring limited travel of the contact 12 with respect to its supporting bi-metal 6. Figures 2 and 4 show the strip 13 in its unstressed and unassembled condition. The portions of the strip 13b and 13c forming opposite sides of the loop are shown as bent to form approximately an angle of 70° in the unstressed condition. When the strip is to be assembled, the portions 13b and 13c are forced toward each other, with the tapered portion 13c stressed slightly also laterally so that the tip end 13a slides underneath the lip 16 of the detent in a manner analogous to closing of a safety pin as clearly shown in Fig. 3. It will thus be seen that the spring loop tends to maintain following engagement of the contacts 11 and 12 as the bi-metals are warped incidental to heating of the coil 10 and changes in ambient temperature, the latter being compensated by the bi-metal 6.

The present invention is especially adapted for controlling certain types of precision circuits wherein variations in resistance at the contacts cannot be tolerated. For maintaining the contact resistance substantially constant, the contacts 11 and 12 are maintained at substantially constant pressure engagement throughout their contacting period. This is accomplished by the special configuration of the spring strip 13 which, in its preferred form extends from the secured part at 14 a short distance at an acute angle, as indicated at 13d, from the bi-metal 6 and then extends (as portion 13d) generally parallel and in spaced relation to the bi-metal for a distance approximately half the distance in the example shown between the secured part at 14 and the bi-metal base. However it should be understood that the length of the spring loop is not necessarily related to the length of the supporting bi-metal. The spring strip at the low portion of the loop is bent backward so that the portion 13c forms with portion 13b an elongated compressed loop as shown. The resiliency of the loop at its lower portion is relatively greater than that of the portions 13b and 13c by reason of reinforcing means, such as ridges 13e pressed in the aforesaid side portions. The ridges 13e as shown extend longitudinally along the center axis of said portions for a distance depending on the required spring characteristics of the contact mounting.

The operation of the thermal time delay switch will now be briefly described: assuming first that the heater coil 10 is energized, the resulting heat causes warping of the bi-metal 5 toward the right so that contact 11 engages contact 12. As the bi-metal 5 continues to warp in this direction the contact 11 moves the contact 12 also toward the right so that the prestressed spring loop is further tensioned, the travel of the engaged contacts away from the detent lip 16 depending on the heater and the characteristics of the bi-metal 5. Ambient temperature

changes are compensated by the bi-metal 6 which is adapted to warp in the same direction as the bi-metal 5 for a given temperature change, thereby tending to maintain the distance between the free ends of the bi-metals approximately constant.

Upon deenergization of the heater the bi-metal 5 begins to cool and thereupon to warp slowly toward the left with the contact 12 in following engagement with contact 11 until the free loop end 13a engages the restraining detent lip 16. During this following engagement the contact pressure remains substantially constant due to the configuration of the spring mounting above described. When the travel of contact 12 is blocked, further cooling of the bi-metal 5 causes separation of the contacts and opening of the control circuit according to the prescribed time delay.

It should be understood that this invention is not limited to specific details of construction and arrangement thereof herein illustrated, and that changes and modifications may occur to one skilled in the art without departing from the spirit of the invention; for example the spring loop 13 may be mounted if desirable, on the bi-metal 5 having the heater coil, the relative movement of the contacts being essentially the same in both instances; also if desired, the device may be readily adapted to have the contacts normally closed, rather than open as shown. That is the bi-metals are simply turned around so that with the heater cold and the contacts positioned so as to engage, the bi-metals warp toward the left rather than toward the right as shown, upon increase in temperature to open the contacts.

What is claimed is:

1. A thermal time delay switch comprising a supporting base, a first bi-metal element and a second bi-metal element, said elements arranged so as to extend generally in the same direction in spaced relation to each other and each element being supported on said base at one end so that the free ends are moveable relative to each other, a heater element adjacent said first bi-metal element arranged to cause warping of the free end thereof relative to the free end of said second bi-metal element, said second bi-metal element being influenced primarily by ambient temperature so as to warp in the same direction as said first element for a given change in ambient temperature, a first switch contact mounted on one of said bi-metal elements adjacent the free end thereof so as to be positioned therewith, a co-acting switch contact carried by the other bi-metal element, and means for mounting said co-acting contact on said other bi-metal element for relative movement thereto comprising a resilient member secured at one part thereof to said other bi-metal element and arranged to form a loop extending from the secured part toward said base, detent means secured to the free end of said other bi-metal element and adapted to be engaged by the free loop end of said member so as to limit the expansion of said loop,

said free end of the loop member carrying the co-acting contact in alignment with said first switch contact so that said contacts are adapted to be in following engagement for a limited travel as determined by the position of said detent, said loop arrangement being adapted to ensure substantially constant pressure between said contacts during said following travel incidental to relative warping movement of the bi-metal elements.

5 2. A thermal time delay switch as specified in claim 10 1 wherein the resilient member forming the loop is a spring strip extending a material distance from said secured part toward the base.

10 3. A thermal time delay switch as specified in claim 2 wherein the spring strip is offset at an acute angle from 15 said other bi-metal element adjacent the secured part.

4. A thermal time delay switch as specified in claim 1 wherein the resilient member forms an elongated compressed loop extending approximately half the distance from the secured part toward the base.

20 5. A thermal time delay switch as specified in claim 1 wherein the detent and resilient member are formed as a continuous spring strip forming a closed loop of the safety pin type, said strip being attached to said other bi-metal element at the aforesaid secured part.

25 6. A thermal time delay switch as specified in claim 2 wherein the spring strip extends for a short distance from the secured part at an acute angle from the strip and then extends generally parallel to the strip in spaced relation thereto for a material distance towards the base, thereupon looping in reverse direction to engage and be restrained from further expansion by an overhanging lip of said detent, thereby providing for relative movement of the co-acting contact with respect to said other bi-metal elements and restraint of following movement of the contact with respect to the first contact.

30 7. A thermal time delay switch as specified in claim 2 wherein the spring strip at opposite sides of the loop is provided with reinforcing portions extending longitudinally of the strip and terminating short of the end of the loop so as to increase relative resiliency at said loop end.

35 8. A thermal time delay switch as specified in claim 7 wherein the loop portion extending from the secured part toward the loop end is offset in spaced substantially 40 parallel relation to said other bi-metal element.
